(57) **CLAIM**

An ornamental design for a modular racking system, as shown and described.

DESCRIPTION

FIG. 1 is a front-bottom isometric view of a first embodiment of my modular racking system.

FIG. 2 is a front view of the embodiment.

FIG. 3 is a rear view of the embodiment.

FIG. 4 is a left side view of the embodiment.

FIG. 5 is a right side view of the embodiment.

FIG. 6 is a top view of the embodiment.

FIG. 7 is a bottom view of the embodiment; and, FIG. 8 shows the embodiment installed attached to a seat of a vehicle.

In the drawings, the broken lines in FIG. 8 depict firearms and a seat that form no part of the claimed design.

Broken lines are not intended to represent claimed subject matter.
